UNITED STATES PATENT OFFICE.

ERNEST A. WALKER, OF NEWARK, NEW JERSEY, ASSIGNOR TO THE G. & G. FIXTURE CO., A COPARTNERSHIP COMPOSED OF WILLIAM GOLDBERG AND ABE GOLDBERG, OF NEWARK, NEW JERSEY.

DESIGN FOR A BRACKET BACKPLATE FOR LIGHTING FIXTURES.

Application filed May 9, 1924. Serial No. 9,539. Term of patent 7 years.

To all whom it may concern:

Be it known that I, ERNEST A. WALKER, a citizen of the United States, residing at 762 Summer Avenue, Newark, in the county of Essex and State of New Jersey, have invented a new, original, and ornamental Design for a Bracket Backplate for Lighting Fixtures, of which the following is a specification, reference being had to the accompanying drawing, forming part thereof.

Fig. 1 is a front view of a bracket backplate for lighting fixtures, showing my new design. Fig. 2 is a side view thereof.

I claim:

The ornamental design for a bracket backplate for lighting fixtures, as shown.

In witness whereof, I hereunto subscribe my name, as attested by the two subscribing witnesses.

ERNEST A. WALKER.
